UNITED STATES PATENT OFFICE.

HENRY CHANNON, OF CHICAGO, ILLINOIS.

EXCAVATING-BUCKET.

No. 832,894.

Specification of Letters Patent.

Patented Oct. 9, 1906.

Application filed July 9, 1906. Serial No. 825,392.

To all whom it may concern:

Be it known that I, HENRY CHANNON, a citizen of the United States, residing at Chicago, county of Cook, State of Illinois, have invented a certain new and useful Improvement in Excavating-Buckets; and I declare the following to be a full, clear, and exact description of the invention, such as will enable others skilled in the art to which it pertains to make and use the same, reference being had to the accompanying drawings, which form a part of this specification.

My invention relates in general to excavating apparatus, and more particularly to an excavating-shovel.

In the work of excavating it is necessary that the shovel or bucket should be forced into the material until filled, then held into position to retain the material therein while being moved over the spoil-pile, and then permitted to dump the material therefrom.

The primary object of my invention is to provide an improved excavating-shovel which may be readily loaded with material, which may be securely held in a substantially horizontal position when loaded, and which may be easily dumped when above the position where the material is to be deposited.

A further object of my invention is to provide an excavating-shovel which will be simple in construction, inexpensive in manufacture, and efficient in use.

The embodiment of my invention herein disclosed may be generally described as comprising a shovel, a supporting-bail between the arms of which the shovel is pivotally supported at the rear of its center of gravity, a bell-crank lever on each side of the shovel, one arm of the lever being pivoted to the shovel, a link connecting the bell-crank lever adjacent its angle with the bail above its fulcrum, and hauling mechanism connected with the other arm of the bell-crank lever on each side of the shovel.

My invention will be more fully described hereinafter with reference to the accompanying drawings, in which the same is illustrated as embodied in a convenient and practical form, and in which—

Figure 1 is a side elevational view showing the bucket in position to dig into the material; Fig. 2, a view similar to Fig. 1, showing the bucket when filled with material; Fig. 3, a front elevational view of the bucket, part be-

ing broken away; Fig. 4, a view similar to Figs. 1 and 2, showing the bucket in dumping position; Fig. 5, a front elevational view looking from the left in Fig. 4, part of the device being broken away; and Fig. 6, a view of a modification.

The same reference characters are used to designate the same parts in the several figures of the drawings.

Reference-letter A indicates a bucket or shovel of any desired shape and size and made of any suitable material. The bucket is preferably made of sheet metal and is provided with side walls A¹ and A² and a curved bottom wall a, having a cutting edge at the front thereof. In order to impart the necessary strength to the front of the bucket, it is provided with a plate A³, comprising portions riveted to the outer surfaces of the sidewalls of the bucket and with an integral intermediate portion extending above the side walls.

B designates a bail for supporting the bucket, between the ends of which the bucket is pivotally mounted. Each end of the bail extends between an ear b, securely fastened to the bucket and the adjacent side wall. A pin extends through registering holes in the ear b, lower end of the bail, and adjacent side wall of the bucket. The bail B is preferably constructed as shown in Fig. 5, in order that it may have the requisite strength. Reinforcing-braces B¹ and B² are secured to the side portions of the bail and are united at their converging ends to a strut B³, the lower end of which is riveted to the horizontal portion of the bail. Suitable lifting means, such as a cable F, is secured to the bail in any suitable manner, as by means of a ring b⁴, extending through the united ends of the braces B¹ and B² and the strut B³.

A bell-crank lever C is pivotally secured in any convenient manner to the outer surface of each of the side walls of the bucket near the front thereof. The end of one arm c¹ of each bell-crank lever is shown as pivotally supported by a pin extending through registering holes in the lever and in the side wall of the bucket and an ear c, riveted to the bucket, the end of the lever lying on the outside of the ear c. The arms c² of bell-crank levers on the opposite sides of the bucket are united by a bail C¹, preferably formed integrally with the levers. Suitable hauling

means—such, for instance, as a cable E—is secured to the bail C' in any suitable manner, as by means of a ring e.

A link D connects each bell-crank lever 5 with the portion of the bail B on the corresponding side of the bucket. One end of the link D is pivotally connected by a screw-threaded bolt d^2 to the bail at a point a short distance from its fulcrum. The opposite end 10 of the link D is pivotally secured by screw-threaded bolt d' to the bell-crank lever at a point adjacent its angle.

The manner of using and operation of my improved excavating-bucket are as follows: 15 The bucket is located at the point where the material is to be removed by means of the lifting-cable F, which depends from a derrick, crane, or other supporting mechanism. The shovel or bucket is then moved horizontally 20 by power applied to the hauling-cable E, which is operatively connected to a windlass or other power device. The horizontal movement of the bucket causes it to dig into the earth or other material, thereby filling 25 the bucket. After the bucket has been filled the tension of the hauling-cable E causes the bucket to assume a substantially horizontal position, such as shown in Fig. 2, owing to the links D, which connect the bell-crank levers with the bail. The bucket while held in 30 a substantially horizontal position may be moved to the desired position where the material is to be deposited when the tension on the hauling-cable E is discontinued, thereby 35 permitting the bucket to swing relatively to the bail to the position shown in Fig. 4, when the material will at once fall from the bucket. It is obvious that when the bucket is in the substantially horizontal position shown in 40 Fig. 2 it cannot oscillate between the arms of the bail B without the ends of the links D^2 , which are pivotally connected to the bails, moving toward the rear of the bucket. Such rearward movement of the links is prevented 45 as long as the bell-crank levers are retained in the position shown in Fig. 2. When, however, the tension on the hauling-cable is discontinued, the bell-crank levers are permitted 50 to oscillate rearwardly, and hence permit the links to move toward the back of the bucket, thereby permitting the bucket to swing downwardly and dump the material.

The cable E, bail C, together with the bell-crank levers, and links D constitute the pulling mechanism by means of which the bucket is hauled horizontally and loaded with material.

From the foregoing description it will be observed that I have invented an improved 60 excavating-bucket which though simple in construction may be readily loaded with material and when loaded securely held in position to retain the load until it is desired to dump the material, which may be done by

merely discontinuing the tension upon the 65 hauling-cable.

In Fig. 6 I have illustrated a modified form of my invention, in which the bell-crank lever is fulcrumed intermediate of its angle and the end of its short arm. In this view H indicates the bell-crank lever, fulcrumed at h upon the bucket and connected at the end h' of its short arm with the link D. The operation of this modification of my invention is the same as above described with respect to 70 the form of the invention shown in Figs. 1 to 5, except that, when the bucket dumps, the bail uniting the ends of the long arms of the bell-crank levers swings downwardly and not 75 upwardly.

It is obvious that the bell-crank levers may be connected to the links D at the ends of their arms and fulcrumed at a point intermediate of their angles and their connections with the links, as shown in Fig. 6. In this 80 figure H indicates one of the bell-crank levers which is fulcrumed upon the side of the bucket at h and pivotally connected to the link D at the end h' of one of its arms. The operation of this modification of my invention is the same as that above described, except that the bail C' swings downwardly relative to the bucket instead of upwardly. 85

Having now fully described my invention, what I claim as new, and desire to secure by 90 Letters Patent, is—

1. In a device of the character described, the combination with an excavating-shovel, of a supporting member pivoted to said shovel at the rear of its center of gravity, and 100 hauling mechanism secured to said supporting member and connected to the shovel at the front of its center of gravity.

2. In a device of the character described, the combination with a shovel, of a supporting-bail, between the arms of which said shovel is pivoted at the rear of its center of gravity, and pulling mechanism secured to the portions of said bail on the opposite 105 sides of the shovel, said mechanism being connected to each side of the shovel at the front of its center of gravity.

3. In a device of the character described, the combination with a shovel, of a supporting-bail to the arms of which said shovel is 110 pivoted at the rear of its center of gravity, a lever pivotally connected to said shovel in front of said bail, a link pivotally connecting said bail and lever and means connected to said lever to which the hauling power is applied. 115

4. In a device of the character described, the combination with a shovel, of a supporting-bail between the arms of which said shovel is pivoted at the rear of its center of 120 gravity, a bell-crank lever pivotally connected to said shovel in front of said bail, a link pivotally uniting said bail and lever and

means connected to said lever by means of which hauling power is applied.

5. In a device of the character described, the combination with a shovel, of a supporting-bail between the arms of which said shovel is pivoted, at the rear of its center of gravity, a bell-crank lever on each side of said shovel fulcrumed thereon at the end of one arm thereof, a link pivotally connecting each bell-crank lever adjacent its angle to

the corresponding arm of said bail, and means connected to the other arms of said bell-crank levers for applying hauling power to the shovel.

In testimony whereof I sign this specification in the presence of two witnesses.

HENRY CHANNON.
